UNITED STATES PATENT OFFICE.

ARTHUR A. OLSON, OF CHICAGO, ILLINOIS, ASSIGNOR TO JACQUES ROUSSE, OF LOS ANGELES, CALIFORNIA.

TOWEL-CABINET.

1,295,578.

Specification of Letters Patent. Patented Feb. 25, 1919.

Application filed January 8, 1918. Serial No. 210,825.

To all whom it may concern:

Be it known that I, ARTHUR A. OLSON, a citizen of the United States, and a resident of the city of Chicago, county of Cook, and State of Illinois, have invented certain new and useful Improvements in Towel-Cabinets, of which the following is a specification.

My invention relates to improvements in towel cabinets, of the type designed for use in dispensing individual towels, that is a clean individual towel to each user.

The object of the invention is the production of a towel cabinet as mentioned, which will be of durable and economical construction and efficient in use.

Other objects will appear hereinafter.

The invention consists in the combinations and arrangements of parts hereinafter described and claimed.

The invention will be best understood by reference to the accompanying drawings forming a part of this specification, and in which,

Figure 1 is a partially sectional side elevation of a towel cabinet embodying one form of the invention,

Fig. 2, a front elevation of Fig. 1,

Fig. 3, a vertical section through another form of cabinet embodying the invention,

Fig. 4, a front elevation of Fig. 3, and

Fig. 5, a fragmental section illustrating a modified form of the construction seen in Figs. 3 and 4.

The form of the construction illustrated in Figs. 1 and 2, comprises a cabinet consisting of a rear vertical wall or body 6 adjacent the upper end of which is provided a forwardly projecting shelf 7, which is adapted, when the cabinet is in use, to support a stack of towels 8 as illustrated. At the sides of the support 7 are provided side pieces or flanges 9 to hold the towels against lateral displacement from said support. At the front side of support 7 are provided two vertically extending posts 10 which serve to hold the towels against forward horizontal displacement from support 7, said posts 10 being rigidly secured at their lower ends to said support, as seen in Fig. 2.

Each towel 8 is provided adjacent its front edge with a centrally positioned grometed opening 11, through which a flexible retaining member 12, in the form of a chain, is adapted to be passed, said chain, after

passing upwardly through the holes in the towels, being brought forward and then downward loosely, the same depending into an upwardly opening soiled towel receptacle 13 provided at the lower end of the cabinet. The two ends of the chain are locked together by a padlock 14. In order to accommodate the chain, the support 7 is provided at its front edge with a forwardly opening central notch 15, through which the chain is adapted to loosely pass. The posts 10 are spaced apart so as to form a vertically extending slot 16 between the same, which permits of free passage and free vertical movement of the chain, the arrangement, in other words, being such that the upper portion or bight of the chain will be unsupported, except by the towels through which it passes, the upward extension of the chain being determined by the height of the stack of towels on support 7.

In using the cabinet a bundle or stack of towels may be strung and locked upon the chain at the laundry, the attendant or laundry man placing the stack of towels upon the support 7 with the chain arranged as seen in Fig. 1. A prospective user of a towel needs only to grasp the uppermost towel and bring the same over or between the posts 10, and after use allow the same to drop, when the towel will be guided by the chain into the soiled towel receptacle 13. The towels remaining in the stack, after a towel has thus been removed from the stack, will be held in place against forward horizontal displacement by the posts 10.

In the form shown in Figs. 3, 4 and 5, a cabinet is provided, comprising a body 17, in the upper end of which is provided a shelf or towel support 18. Said support 18 constitutes the bottom of a clean towel receptacle 19, the upper side of which is provided with an upwardly swinging door 20, hinged at 21. The front side of the clean towel receptacle 19 is formed by a forwardly or horizontally swinging door 22, which is hinged at 23, said door being adapted to be locked in closed position by any suitable locking means, such as a padlock 24.

The door 22 is formed with a central vertical slot 25 which extends downwardly from the upper edge thereof, said slot being adapted to accommodate the towel retaining chain 12 in precisely the same manner as the

slot 16 formed between the posts 10 in the form of the construction first described.

In this form of the construction the towel retaining chain passes upwardly through 5 the towels 8, a stack of which is adapted to be accommodated in the receptacle 19 arranged upon the support 18, said chain, after passing upwardly through the towels, being brought forwardly through the slot 10 25, whence the same hangs loosely, passing downwardly into a soiled towel receptacle 26 formed in the lower end of the cabinet. The ends of the retainer chain are, as before, locked together by a suitable locking device 15 14. The forward edge of the support or shelf 18 is formed with a centrally positioned notch 27 through which the chain is adapted to loosely pass, in precisely the same manner as in the form of the construction 20 first described. In order to guide the soiled towels into the receptacle 26, after release by a user, a forwardly projecting inclined chute or lip 28 is provided, leading to said receptacle.

25 In this form of the construction it will be seen that the retainer chain will embrace or encircle the door 22, so that when said door is locked by the lock 24, the retainer chain and hence the towels arranged thereon will 30 be positively locked to the cabinet. In using this form of the cabinet, a user needs only to raise the cover 20, reach into the receptacle 19 and withdraw the uppermost towel from the stack. In so doing the towel 35 is drawn upwardly and forwardly over the door or through the slot 25, the towel after use and release by the user, being guided by the retainer and the chute 28 downwardly into the soiled towel receptacle 26. In order 40 to insure ready engagement of the chain with the slot 25, after each succeeding withdrawal of a clean towel, the upper end of said slot may be flared, as clearly seen in Fig. 4. A corresponding formation of 45 the slot 16, of the first described form, may also be employed for the same purpose. In this form of the cabinet, as in the form first described, the upper end or bight of the retainer chain will be unsupported except 50 by the towels arranged in the clean towel receptacle 19, the upward extension of the chain being determined by the height of the stack of towels. As said stack of towels diminishes, the bight or upper portion of 55 the chain will correspondingly lower by gravity and will be guided in this movement by the sides of slot 16. The gradual lowering of the bight or upper portion of the chain renders it unnecessary for a towel user to lift the towel above the stack; it being possible, in removing the uppermost 60 towel from the stack, to simply draw the same forwardly through the slot between the stops or in the door, as the case may be, at the 65 front of the clean towel support. Also, with

this arrangement, the weight of the towel guide, especially when soiled towels weigh down the lower end thereof, will have a tendency to hold the towels in close, compact arrangement on the clean towel support and will prevent accidental shifting or displacement of the towels from said support.

In the forms of the construction described, it will be seen that the front portion of the chain rests closely against the 75 front side of the cabinet, and thus the free downward sliding thereon of the towel be interfered with. In order to avoid this, however, the front door or towel stop 22 of the cabinet may be inclined forwardly, as 80 seen at 22' in Fig. 5, so that the front portion of the chain in depending from the upper end of the stack of towels, will be held away from the front side of the cabinet, thus allowing for free and uninterrupted 85 sliding of the soiled towels down the same after release by a user.

While I have illustrated and described the preferred forms of construction for carrying my invention into effect, these are 90 capable of variation and modification without departing from the spirit of the invention. I, therefore, do not wish to be limited to the precise details of construction set forth, but desire to avail myself of such 95 variations and modifications as come within the scope of the appended claims.

Having described my invention what I claim as new and desire to secure by Letters Patent is:

1. In a device of the class described, a 100 towel support; a flexible retaining member extending upwardly from said support through the towels arranged on said support and then downwardly beyond the edges 105 of the towels, whereby the upper portion of said retaining member is unsupported except by the towels on said towel support, and the upward extension of said retaining member is determined by the height of the 110 stack of towels on said towel support; and means for holding the towels against horizontal displacement from said towel support, said means being vertically slotted to permit of free downward vertical movement of said retaining member as the number of towels on said support diminishes, substantially as described.

2. In a device of the class described, a 115 towel support; a flexible retaining member extending upwardly from said support through the towels arranged on said support and then downwardly beyond the front edges of the towels, whereby the upper portion of said retaining member is unsupported except by the towels on said towel support and the upward extension of said retaining member is determined by the height of the 120 stack of towels on said towel support; and forwardly inclined means en- 125

gaging with the front edges of the towels for holding the latter against horizontal displacement from said towel support, said means having a slot to permit of free downward vertical movement of said retaining member as the number of towels on said support diminishes, substantially as described.

3. In a device of the class described, a 10 towel support; a flexible retaining member extending upwardly from said support through the towels arranged on said support and then downwardly; and means encircled by said retaining member for holding the 15 towels against horizontal displacement from said towel support and permitting of free downward vertical movement of said retaining member above said towel support as the number of towels on said support diminishes, substantially as described.

4. In a device of the class described, a 20 towel support; a flexible retaining member extending upwardly from said support through the towels arranged on said support and then downwardly; and a horizontally swinging door at the front of said 25 towel support for holding the towels against horizontal displacement from said towel support, said door having a slot extending

downwardly from the upper edge thereof to 30 said support permitting of free passage and downward vertical movement of said retaining member as the number of towels on said support diminishes, substantially as described.

5. In a device of the class described, a 35 towel support; a flexible retaining member extending upwardly from said support through the towels arranged on said support and then downwardly, whereby the 40 upper portion of said retaining member is unsupported except by the towels on said towel support; and means for holding the towels against horizontal displacement from said towel support, said means permitting 45 free downward vertical movement of said retaining member as the number of towels on said support diminishes, and guiding said retaining member in said movement thereof, substantially as described.

In testimony whereof I have signed my name to this specification in the presence of two subscribing witnesses.
